INVENTOR

BY
Pierre Barnes
ATTORNEY

UNITED STATES PATENT OFFICE.

JAMES H. COYNE, OF PORT TOWNSEND, WASHINGTON.

EXCAVATING AND DUMPING APPARATUS.

Application filed February 27, 1922. Serial No. 539,671.

To all whom it may concern:

Be it known that I, JAMES H. COYNE, a citizen of the United States, residing at Port Townsend, in the county of Jefferson and State of Washington, have invented certain new and useful Improvements in Excavating and Dumping Apparatus, of which the following is a specification.

This invention relates to excavating apparatus and its object is, generally stated, the perfecting of apparatus of this character whereby the excavating and handling of material may be more conveniently and economically performed than hitherto.

More specific objects and advantages of the invention will appear in the following specification.

The invention consists in the novel construction, adaptation and combination of parts hereinafter described and claimed.

In the accompanying drawing,—

Figure 1 is a side elevation of apparatus embodying my invention. Fig. 2 is a plan view of the same. Fig. 3 is a transverse sectional view taken substantially through 3—3 of Fig. 1, the scraper being omitted, the elevator being represented in position for dumping a load into a vehicle which is represented in end elevation. Fig. 4 is a view in side elevation of the apparatus shown applied and with the scraper shown in the position it will assume in transporting a load to the elevator. Fig. 5 is a plan view to a larger scale of the elevator regulating devices shown in Figs. 1 and 2.

In said drawings, the reference numeral 10 designates an excavating scraper of a well known type, the same comprising side wall members 11 and a back wall 12 which is preferably of an arcuate shape and may be equipped along one of its edges with digging teeth 13.

The scraper operates to excavate and convey a load of material by being drawn forward or in the direction of arrow in Fig. 4, by means of a power driven drum 15 through the medium of a drag cable 16 which is attached to the scraper bail 17.

A haul-back cable 18 extends from a winding drum 19 to and about a pulley 20 and thence returns as a lead 18¹ which is secured as at 21 to the rear end of the scraper.

The pulley 20 is attached to a post 22, tree or other support at the opposite side of

the excavating work from the position of said operating drums.

These drums constitute elements of a hoisting or hauling engine which, like all of the above mentioned parts may be of any well known or suitable construction. According to the present invention I provide a base frame 23, preferably of wood, having longitudinal side or runner members 23¹. Said engine is secured upon said frame adjacent to one end thereof and rigidly secured to said frame adjacent its other end is a framework which may advantageously be formed of structural steel or iron. As shown in the drawings, said frame work consists of four corner posts 24 which are connected at their lower ends, as by gusset plates 25, to the respective members 23¹ of the base frame.

The upper portions of the posts 24 are rigidly connected to each other by longitudinal and transverse bars 26 and 27. Said framework is furthermore secured by tie rods 28 to the base frame. Provided within said framework is an elevator 29 of substantially rectangular shape in horizontal section, and is formed with a floor 30, a back wall 31 and side walls 32 which extend transversely from said back wall and terminate at opposite sides of an opening 33 located at the front of the elevator which, as shown in Fig. 2, protrudes beyond a side of the framework. At or near the front end of the elevator the same is provided with arms 34¹ upon which are mounted rollers 34 which are arranged to travel in guideways, such as 35, afforded by bracket attachments 36 upon the posts 24 at one side of the framework.

When it is intended, however, to operate the elevator in a reverse position from that in which it is illustrated, bracket attachments 36¹ would be applied to the posts at the opposite side of the framework. The lower portions of said guideways are disposed to be substantially vertical, but the upper portions, denoted by 35¹, are inclined outwardly laterally of the frame whereby in the raising of the elevator the latter is set outwardly with respect to the framework.

Hoisting cables 37, 38, 39 and 40 which are connected to their respective corners, or to extension arms such as 29¹, of the elevator extend upwardly to and about pulleys 41 whence they extend downwardly, as at 37¹,

38¹, 39¹ and 40¹ and thence beneath pulleys or rollers 42, 42¹ and 43 to regulator devices, which are best shown in Fig. 5, and to which reference is now made.

5 The cables 37 and 38, which are connected to the end of the elevator in proximity with the guide rollers 34, are connected to and extend, as at 37² and 38², from one end of a coupling 44. The cables 39 and 40, which 10 are connected to the rear end of the elevator, are extended about a sheave or sheaves 45 and returning as at 39² are connected to and extend from the coupling 44 in opposed relations to the connection therewith of the 15 cables 37 and 38. The sheaves 45 are mounted in a shell 46 which is connected, as at 47, with an end of a controlling cable 48 whose other end extends to and is arranged to be wound about or unwound from a drum 20 49 to effect the raising and lowering of the elevator. Said controlling cable also serves to effect the tilting of the elevator about the axis of the rollers 34, when in the raising of the elevator the rollers 34 are traveling upwardly in the upper portions of the respective guideways and prior to the termination 25 of the upward travel of the rear end of the elevator.

30 To such ends the coupling 44 is formed with or is rigidly connected to a bar 50 which extends through and serves as a guide for the shell 46 which carries the sheaves 45. Provided on the bar 50 is a protuberance 51 which cooperates with a hook 52 to releasably engage a roller 53 which is connected by links 54 to said shell.

35 Said hook is of substantially the shape in which it is shown in Figs. 2 and 5, and has its shank 52¹ pivotally connected by a pin 55 to said coupling so as to enable the hook bill 52² to be swingable toward or from the protuberance 51.

40 The hook is normally retained in its illustrated position with respect to said protuberance by means of an extensible spring 56 for the purpose of releasably engaging and retaining in engagement the roller 53 when the same is in its dotted line 53¹ position, Fig. 5.

45 To release the roller 53, the hook is swung away from said protuberance by means of an arm 52³ on the hook meeting a stationary stop 57 provided in the path of its travel 50 above the base frame. The roller 53 is normally retained in juxtaposition with the bar 50 as by means of a leaf spring 58 and which serves to direct the roller against a bevel face 52⁴ of the hook to swerve the same out 55 of the path of the roller when being brought 60 into position to be engaged by the hook.

65 The action of the regulating device shown in Fig. 5 is as follows: When the elevator is being raised horizontally, the regulator parts occupy the relative positions in which they are shown in Fig. 2, that is to say—

the shell 46 is held in engagement with the coupling 44 by reason of the roller 53, which is carried by the shell, being engaged by the hook 52 and the bar protuberance 51, which are carried by the coupling.

70 This condition obtains until the elevator in its ascent reaches a position whereat the rollers 34 approach the upper ends of the guideways therefor.

75 During the termination of such upward travel of the rollers 34 the hook arm 52³ encounters the stop 57 and is thereby caused to be swerved rearwardly to release the roller 53 from its connection with the coupling. When this occurs the continued pull 80 of the cable 48, which is applied through the medium of shell 46, effects the raising of the rear end of the elevator into the position in which the same is shown in Fig. 3 to dump the material from the elevator into 85 a vehicle such as 60, for example, to be conveyed away.

90 Provided above the elevator floor and between the side walls 32 thereof is a rack consisting of side bars 61 pivotally connected intermediate their lengths, as by pins or bolts 62, to the adjacent side walls of the elevator.

95 The side bars 61 have secured thereto rails 63 which are disposed transversely of the elevator and serve as track elements upon which the excavator scraper travels when drawn by the cable 16 over the elevator to deposit the scraper load thereupon. The rack bar-parts 61¹ at the rear of the 100 elevator, as shown in Figs. 2 and 3, are connected to the ends of ropes 64 whose other ends are connected to the adjacent member 23¹ of the base frame. Said ropes are of less lengths than the vertical travel 105 of elevator whereby the ropes serve in the upward movement of the elevator to raise the rack portion within the elevator so not to interfere with the discharge of material from the latter when the same is tilted as 110 in Fig. 3. For the purpose of directing the scraper from the ground over the end of the base frame and onto the rails 63 of said rack, I provide runways 65 and 66 which are hingedly connected at 67 with each other 115 and to the base frame and I provide at the inner end of the runway 66 an apron extension 68 therefor. This apron is hinged, as at 69, to the runway so as to extend over the adjacent side of the elevator, said apron 120 being advantageously counter weighted by a heavy body 70 so as to facilitate its being turned upwardly by the elevator's ascension and to be readily returned over the same by the scraper when drawn over the apron onto 125 the rails 63.

130 The construction of the invention in its preferred embodiment and the operation of the same will, it is thought, be understood from the foregoing description.

What I claim, is,—

1. In apparatus of the character described, an elevator, a framework in which said elevator operates, power operated cables for elevating the elevator, means provided on said framework for guiding the elevator in vertical and lateral directions successively, and controlling devices actuated by the movement of the cables and cooperating with said means to effect the tilting of the elevator during the lateral movement of the same.
2. The combination with an elevator, a power operated drum, and cables operatively connecting said elevator with said drum, of elevator controlling means connected to said cables, and a stop cooperating with said controlling means to effect the tilting of the elevator in proximity with the end of its upward travel.
3. The combination with an elevator, a framework, brackets rigid with the framework, said brackets being provided with guideways, and cables for hoisting said elevator, and means carried by said elevator and operating in the bracket guideways, said means being engageable with the brackets at the upper ends of the respective guideways to limit the elevation of one end of the elevator whereby the tilting of the elevator is effected by the elevator hoisting cables.
4. In apparatus of the character described, an elevator, cables respectively connected to the front and rear ends of the elevator for suspending the same, guide pulleys for said cables, a coupling to which all of said cables are connected, a shell, a sheave provided in said shell for leading the cables from the rear end of the elevator to said coupling, a power operated cable connected to the shell for actuating the aforesaid cables to raise or lower the elevator, means for releasably connecting said coupling to said shell, and means rendered operative by said power cable in the hoisting of the elevator to effect the disengagement of the first named means with respect to the coupling and shell whereby the cables from the rear end of the elevator are actuated to effect the tilting of the elevator.
5. The combination with an excavating scraper, an elevator, means for operating said scraper and for hauling the same onto and from the elevator, and means for successively hoisting and tilting the elevator,
- of a frame pivotally connected to said elevator and serving to support said scraper in spaced relations above the elevator floor, and means rendered operative in the upward travel of the elevator for tiltably raising said frame with respect to the elevator floor.
6. The combination with an excavating scraper, an elevator, means for operating said scraper and for hauling the same onto and from the elevator, and means for raising and lowering the elevator, of a frame pivotally connected to said elevator and serving to support said scraper in spaced relations above the elevator floor, and means rendered operative in the upward travel of the elevator for tiltably raising said frame with respect to the elevator floor.
7. In apparatus of the character described, the combination with an excavating scraper and means for operating the same, of an elevator, means for directing said scraper into a position to deposit its load upon the elevator, means for guiding the elevator in its vertical movements, and hoisting means cooperating with the elevator guiding means whereby said elevator is tilted into a dumping position in the upward travel of the same.
8. In apparatus of the character described, a base frame, framework secured upon said base frame, an elevator mounted for vertical movements in said framework, rollers provided upon said elevator adjacent to one end thereof, means rigid with said framework to receive said rollers and serving to guide said elevator in vertical and horizontal directions, and elevator hoisting means, said hoisting means comprising a power operated hoisting drum, a main cable adapted to be wound upon said drum, elevator supporting cables respectively connected to the front and rear ends of the elevator, operative connections between the main cable and said supporting cables, said operative connections including regulating devices, and means rendered operable by the main cable in effecting the elevation of the elevator whereby said regulating devices are influenced to cause the front and rear ends of the elevator to be raised to unequal heights.

Signed at Port Townsend, Washington,
February, 1922.

JAMES H. COYNE.
